UNITED STATES PATENT OFFICE

173,134

SHOE SOLE

Eldon L. Babcock, Binghamton, N. Y., assignor to Gro-Cord Rubber Company, Lima, Ohio, a corporation of Ohio

Application March 31, 1954, Serial No. 29,787

Term of patent 14 years

(Cl. D7—5)

To all whom it may concern:

Be it known that I, Eldon L. Babcock, a citizen of the United States of America and a resident of Binghamton, in the county of Broome and State of New York, have invented a new, original, and ornamental Design for a Shoe Sole, of which the following is a specification, reference being had to the accompanying drawing, forming part thereof, in which:

Fig. 1 is a bottom plan view of a shoe sole embodying my new design, and

Fig. 2 is a longitudinal section thereof on line 2—2, Fig. 1.

I claim:

The ornamental design for a shoe sole, substantially as shown.
